UNITED STATES PATENT OFFICE

JOHN V. STOUT, OF EASTON, PENNSYLVANIA.

ELECTRIC TEMPERATURE-REGULATOR.

SPECIFICATION forming part of Letters Patent No. 448,274, dated March 17, 1891.

Application filed January 31, 1890, Serial No. 338,763. (No model.)

To all whom it may concern:

Be it known that I, JOHN V. STOUT, a citizen of the United States, residing at Easton, in the county of Northampton and State of Pennsylvania, have invented an Electrical Regulator for Temperature, &c., fully set forth in the following specification, and illustrated in the accompanying drawings.

10 in which a thermostatic circuit-closer is placed at the point where it is desired to keep the temperature within certain predetermined limits, said circuit-closer being in a circuit leading to the magnet controlling the heating medium. My invention is not, however, confined to this particular use, since it may be applied in other ways, as will be hereinafter described.

The object of my invention is to provide a circuit-controller whereby the danger of waste of battery is avoided, the contacts are kept clean by rubbing against each other, and the operation is rendered certain, and, further, to provide a simple and efficient arrangement of circuits for operating the system, all as hereinafter fully set forth.

In the drawings, Figure 1 is a general view of the system. Fig. 2 shows a detail of the circuit-controller.

30 The apparatus at the left of Fig. 1 is placed at the point where the temperature is to be maintained within predetermined limits. The apparatus at the right of Fig. 1 is placed at any suitable point to control the dampers of the heating furnace or valves in steam, water, hot air, or other pipes, or in any other way to regulate the heating medium.

In the first-mentioned apparatus, upon a suitable base, is mounted a clock-work, the motive power of which is kept normally in an active condition for the purpose of actuating one of the movable parts of the circuit-controller when released by the energization of magnet C, mounted on the same base and provided with a pivoted armature II and escapement 1.

2 is an ordinary fly or speed-regulator for the clock-work. This motor-driven part of the circuit-controller consists in a plate 17 on 5° an arbor 3 of the motor, with three radial arms symmetrically arranged—that is, one

hundred and twenty degrees apart—or a different number of arms symmetrically arranged and carrying, preferably, in upwardly-projecting ears adjustable contact-points *e h 55 g*. The co-operating part of the circuit-controller comprises a thermostatic bar or coil 4, which is insulated from the frame of the apparatus and is connected to line. This thermostatic device is composed of two metals of different expansibility, as is well understood, or of any other suitable expansible device. As clearly shown at *f*, in Fig. 2, the ends of the **U**-shaped terminal of the thermostatic bar project beyond the main body of said terminal, and it is this part *f'* which preferably forms the electrical contact with the screw *e*, *h*, or *g*, as the case may be, when the temperature rises or falls beyond the predetermined limit. 60 65 70

55 are mere mechanical limiting-stops for bar 4, and are never in the electrical circuit.

A' A^2 is a second magnet, preferably, though not necessarily, mounted on the same base with the parts before mentioned. This I term a "shunting-magnet," since at certain times it shunts the thermostatic contact. Between the two cores of this magnet the wire is connected with the yoke, as at E. When the armature is attracted, it makes electrical contact with the cores, thus closing a shunt-circuit through the wire b . Between magnets A' , A^2 , and C is a branch k , leading from wire i to frame G of magnet C. 75 80

At some convenient point in the main circuit 77 is placed a battery B or other source of current-supply. This is preferably near the valve-controlling apparatus, as shown in the drawings. From the battery a wire extends to magnet D, the armature 8 of which controls the clock-work escapement 9 and shunting-switch I J, through the medium of angle-lever 10, rigidly connected with the armature. The shunting-switch comprises, in any suitable form, first, a contact, as I, connected by a branch c to the main circuit between the battery and high-resistance magnet D, which contact in its condition of rest maintains the shunt-circuit open, and, second, a metallic co-operating part or element, as J, preferably connected with the frame of the clock-work, and thence through wire d to the

other side of the main circuit. The main circuit is connected to the magnet-yoke between the coils of the magnet, as at 11.

12 is a connecting-rod extending from the 5 crank 13, driven by the clock-work to the valve-handle 14 in the pipe 15.

I will now describe the operation of the system set forth. The system being in its normal condition, as shown in Fig. 1, suppose 10 that the temperature rises so as to expand the thermostatic bar 4 and throw its end against contact *e*. This closes the main circuit through magnets A' , A^2 , C , and D , in series, but magnet D and coil A' are preferably wound to a higher resistance than A^2 15 and C , and the armatures and retracting-springs are so adjusted that the current on line when the three magnets are in circuit will move armatures F and 8 , but will not move armature H . The first effect of closing 20 the circuit at *e* will therefore be to attract armatures F and 8 . The first-named armature, by contact with the magnet-cores, completes a shunt around the contacts *e f'*, as 25 follows: From point *E*, through the core and armature F , and thence by wire *b* to the other side of main circuit 7. This circuit also removes the resistance of coil A' from the line. The shunt by cutting out 30 the thermostatic contacts saves them from burning. It also insures a more perfect circuit for the energization of magnet D , since the contact at *e f'* may be slight and maintains the circuit closed until the completion 35 of the operation. The coils A' , A^2 need not be wound to different resistances. They would operate in the same manner as described if wound alike; but in actual use it is found best to wind them as first described. While 40 the magnet A' , A^2 is advantageous in practice, it may be omitted without rendering the system inoperative. In that case the wire *i* would be connected directly to plate 3, as shown by dotted line 18, and wire *k* would be omitted. 45 Simultaneously with the above operation, or practically so, is the movement of armature 8 , which releases detent 9 of the motor at the furnace or other point, and the clock-work begins to move and brings the main surface 50 or periphery of the disk 16 under the lower arm 10. This renders it impossible for the clock to be stopped until it has made a half-revolution—that is, until the second notch in the disk comes under arm 10—and by this 55 half-revolution the valve-arm 14 is raised, closing the valve and shutting off the heating medium. The heating medium being thus shut off, the temperature at the thermostat soon begins to fall and the thermostatic bar 60 begins to move in the opposite direction. As contact J , which is preferably on the same shaft as disk 16, but in a different vertical plane, revolves, it comes under contact-spring I . This closes a shunt around magnet D , as 65 follows: Wire *c c*, spring I , conducting-plate J , frame of clock-work, and wire *d*, back to the opposite side of the main circuit. This

results in removing the resistance of D from the line, thus increasing the strength of the current and energizing magnet C sufficiently 70 to attract its armature, thereby releasing its clock-work. This clock-work is so geared to the revolving contact-piece 17 that each time it is released by this escapement it revolves said contact-piece one-sixth of a revolution, 75 thus removing *e* out of the path and range of movement of bar 4 in the direction of arrow *x*. By moving *e* out of the path of movement of bar 4, all strain to the apparatus and the permanent disarrangement of the tension of 80 the thermostatic bar due to said continued movement is avoided. To prevent an extreme movement of the thermostatic bar from any cause, I place on either side at suitable distances the mechanical stops 55, which are 85 generally adjusted to allow a range of motion due to a change of temperature of from 60° to 80° . Since the movement above described occurs while *e* and *f'* are together, *e* will sweep across *f'*, and thus by friction keep the surfaces free from dust, bright, and in good condition for electrical contact. The movement already set forth of the contact-plate at the same time that it moves *e* from the path of movement of the bar in the direction of arrow *x* moves *g* into the path of the bar when it moves in the opposite direction—that is, in the direction of the arrow *y*—which occurs when the temperature falls toward the minimum limit, owing to shutting off the heating 95 medium, as already described, or turning on a cold blast, or from any other cause.

When armature H is drawn to the face of its magnet, it closes a shunt, as follows: The main line passes through coils C , a branch *k* 105 leads to the frame G of the magnet, thence from the cores to the armature, through the armature and clock-work to the revolving contact-plate to bar 4, and to line, the contact at *e f'* not having been yet broken. This 110 cuts out magnet A' , A^2 and allows armature F to drop to its normal position, thus opening the shunt which was closed by said armature. At the same time the armature releases the clock-work, breaking the circuit at *e f'*, 115 whereupon armature H is retracted by the force of its spring, and the clock-work is arrested at the close of one revolution. The system is now in condition to operate in the same way for turning on heat when bar 4 120 moves in the direction of arrow *y* to bring *f* in contact with *g*.

With the circuit - controlling apparatus which I have described I employ but one circuit and source of electrical current both for 125 the opening and the closing of the valve, and this circuit is continuous, except at the circuit-controller.

It will be evident that the element 4 instead of being a thermostatic bar, may be an 130 ordinary pressure-gage or other device which is thrown in one direction or the other by the increase or decrease of any force applied to it, the intensity of which force can be regu-

lated. It will also be evident that the system would operate to open and close the valve once if contact *h* were omitted, and it is evident that any odd number of arms may be 5 employed for continuous operation of the apparatus, the gearing being modified according to the number of arms used.

In my application No. 338,762 is shown apparatus having certain features in common 10 with this case, but embracing also additional features and different circuit-connections. In that case also is a generic claim to my circuit-controller and a generic claim to a system of the character herein described having 15 a single circuit and a source of current, and the above features are not claimed herein.

Having thus described my invention, what I claim is—

1. The combination, in a regulator, of a 20 thermostatic bar having conducting terminals, a revolute plate having co-operating contacts, and means for turning said plate, whereby one of said co-operating contacts rubs across one of said terminals and is carried 25 out of the path of movement of the bar and another contact is brought into the path of the bar on its return movement, substantially as described.

2. The combination, in a regulator, of an 30 expansible device terminating in two conducting-arms, a revolute plate between said arms having co-operating contacts, a circuit connected to the bar and to the plate, and a motor for moving said plate, substantially as 35 described.

3. The combination, in a circuit-controller, of an expansible member connected to the circuit and terminating in arms each having a contact-point, and a revolute member having 40 co-operating contacts symmetrically arranged and connected to the opposite terminal of the circuit, substantially as described.

4. The combination, in a circuit-controller, 45 of an expansible member terminating in an electrical contact which is extended to one side of the main body of said member, a movable co-operating contact, and means for moving the same out of the path of movement, substantially as described.

5. The combination, in a circuit-controller, 50 of an expansible member having electrical contact-points connected to a circuit, a revolute member provided with co-operating contacts, a motor for revolving the same, and an escapement which by its movement permits a partial revolution of the revolute member, substantially as described.

6. The combination, in a circuit-controller, 60 of an expansible member connected to the circuit, a co-operating movable member connected to a second terminal of the circuit, and a mechanical stop independent of the circuit for each side of the expansible member, substantially as described. 65

7. The combination, in a regulating system, of a thermostatic circuit-controller, a regulator, a motor therefor, a circuit including a battery and three magnets, one magnet being at the regulator and controlling the motor and two of the magnets being adjacent to the circuit-controller, a shunt to the thermostatic circuit-controller controlled by one magnet, and a mechanical motor operatively connected to one contact of the circuit-controller and controlled by the third magnet, substantially as described. 75

8. The combination, in a regulating system, of a circuit-controller having a movable member, a motor operatively connected thereto, a magnet and detent armature, a second magnet of higher resistance than the first and in series therewith, a shunt, and a circuit-closer therefor for removing resistance from the line, substantially as described. 85

9. The combination, in a regulating system, of a circuit-controller comprising an expansible member and a co-operating revolute member, of a shunt for the contact, said shunt being closed by a magnet in the line, 90 substantially as described.

10. The combination of a motor, a releasing-magnet, armature, a detent, a second magnet in series with the first, an armature therefor which is more readily attracted than the first armature, a circuit closed by the second armature, and a shunt around the second magnet closed by the armature of the first magnet, substantially as described. 95

11. The combination, in a regulating system, of a valve controlling the heating medium, a motor for opening and closing said valve, a detent for the motor, a magnet, an armature for moving said detent, and a circuit-closer on the motor-shaft, one member of the 100 circuit-closer being connected to the main circuit between the battery and detent-magnet, and the other member being connected to the circuit on the opposite side of said magnet, 105 substantially as described. 110

This specification signed and witnessed this 29th day of January, 1890.
